UNITED STATES PATENT OFFICE.

EMILE PASSMANN, OF BAY SAINT LOUIS, MISSISSIPPI.

SPRINKLING-HEAD.

1,200,972.

Specification of Letters Patent.

Patented Oct. 10, 1916.

Substituted for application Serial No. 99,151, filed May 22, 1916. This application filed July 15, 1916. Serial No. 109,443.

To all whom it may concern:

Be it known that I, EMILE PASSMANN, a citizen of the United States, and a resident of Bay Saint Louis, in the county of Hancock and State of Mississippi, have invented a certain new and useful Improvement in Sprinkling-Heads, of which the following is a specification.

The present invention relates to irrigating and sprinkling and has particular reference to new and useful improvements in sprinkler heads.

The primary object of my invention is to provide a new and improved type of sprinkling head having controlling means associated therewith, said head being adapted for application to sprinkling carts and the like or to garden hose.

Another object of my invention is to provide a sprinkling device of the character described having new and improved controlling means whereby a greater or smaller flow of liquid may be obtained, the nozzle proper being divided into a plurality of compartments which may be independently controlled.

A further object of my invention is to provide a plurality of nozzles for detachable association with the sprinkler nozzle for increasing the sprinkling range of the device, the last mentioned nozzles being independently controlled.

A still further object of my invention is to provide a device of the class described which is simply constructed, strong and durable, cheap to manufacture, and effective in operation.

In the various modifications of my invention described in detail hereinafter it will be apparent that I have provided a sprinkler of the class described which may be used as a hand sprinkler in connection with garden hose, or applied to sprinkling carts or the like, or in connection with irrigating and sprinkling systems. It will also be noted that the sprinkler head or body as provided by my invention is divided into a plurality of compartments, the supply of liquid to said compartments being independently controllable whereby to obtain a greater or lesser range of utility. I lay particular stress hereinafter upon the improved manner of controlling the liquid supply, as well as the improved manner of connecting the sprinkler head to various supply pipes.

Another feature of my invention which I lay particular stress upon hereinafter is the simplicity of the device, the wide range of adjustment of the parts not increasing the cost of manufacture to a prohibitive extent.

Other objects and advantages to be derived from the use of my improved sprinkling head will appear from the following detail description and the claims, taken with an inspection of the accompanying drawings, in which:

Figure 1 is a top plan view partly broken away and in section of the preferred form of my invention, showing the same as constructed when applied to a garden hose or the like; Fig. 2 is a transverse vertical sectional view taken on the line 2—2 of Fig. 1, looking in the direction of the arrow; Fig. 3 is a detail perspective view of one of the sprinkler attachments; Fig. 4 is a plan view of a slightly modified form; Fig. 5 is a horizontal sectional view showing a modified form of valve; Fig. 6 is a detail vertical sectional view taken on line 6—6 of Fig. 5; Fig. 7 is a detail perspective view of the outer end of the head shown in Fig. 4, with the perforated caps removed; Fig. 8 is a detail perspective view of the packing strips removed; Fig. 9 is a side elevation, partly broken away and in section, illustrating the application of my invention to a sprinkling cart; Fig. 10 is a view partly in elevation and partly in section through another modified form; Fig. 11 is a detail section through a modified form of valve; Fig. 12 is a detail section taken on line 12—12 of Fig. 10.

Referring more particularly to the drawings wherein similar characters of reference designate like and corresponding parts throughout the various views, 1 designates the body of my improved sprinkling nozzle, the same having a slightly tapered inlet or throat portion 2 connected with a supply pipe 3 by any suitable connection. However, I have provided two forms of connection which may be used in this instance, the same being shown to advantage in Figs. 1, 4, and 10 and described in detail hereinafter.

The body 1 serves to house the supply controlling means for the sprinkler, and to this end is provided with end partitions 4 and 5, the free ends of the pipe sections 6, 7, and 8 being engaged with and supported by said partitions, the front ends of the

pipe sections 6, 7, and 8 extending through the front partition 4 as indicated at 9. The outer free ends of the pipe sections are beveled as at 10 to permit the liquid flowing therefrom to spread.

A valve 11 is interposed in each pipe section 6, 7, and 8 as seen in Fig. 1, said valve being of the turning plug type, the finger piece 14 thereof extending beyond the top wall of the body 1, as seen in Fig. 2. An opening 17 is provided in the bottom wall of the housing 1, said opening being normally closed by a door 18. This allows access to the several valves for inspection and repair. The front ends of the pipe sections 6, 7, and 8 terminate in chambers 19, 20, and 21 formed by vertical partitions 22. The structure of the partitions and the arrangement of the perforated coverings will be described in detail hereinafter, the same being best shown in Figs. 5 and 7.

I provide attachments for use in connection with the form of my invention shown in Figs. 1, 2, and 3 particularly, said attachments being in the form of right angular pipe sections 25 and 26 having sprinkler heads 27 and 28, respectively, rotatably adjustable on the free ends of said pipe sections. The sprinkler heads 27 and 28 are provided with curved perforate caps 29 and 30 and by adjustment may be made to increase the range of the entire device as desired. The inner free ends of the pipe sections 25 and 26 are rotatably connected with pipe sections 31 extending inwardly to the partition 5. Valves 32 are interposed in said pipe sections 31 to control the liquid passing therethrough. Guarding frames 33 extend from the housing 1 and serve to protect the pipe sections 31.

Referring to Fig. 4, I have shown a sprinkler body 35 without guarding frames 33 and side pipes 31, the throat 2 having detachable connection with the supply pipe 3 which, as in Figs. 1 and 2, is adapted to extend into the throat 2, the end of the throat member 2 being provided with a broken bead 38 over which are engaged a plurality of retaining and connecting arms 39 carried by the supply pipe. According to Fig. 4, the supply pipe 3 has a reduced internally threaded end 37 which provides for its connection with a hose.

The body 35 of the modified form in Figs. 5, 6, and 7, like that of Fig. 4 is of a flaring configuration and as in Figs. 1 and 4 is provided with end partitions 4 and 5 in which are carried the free ends of pipe sections 42, 43, and 44. Valve members generally designated 45 are interposed in said pipe sections, said valve members being of a type best shown in Fig. 11 and described in detail hereinafter.

The rear ends of the pipe sections 42, 43, and 44 like pipe sections 6, 7, and 8 of Figs.

1 to 4 communicate with the throat member 2 and the forward ends of said pipe sections extend beyond the partition 4, the free forward ends of said pipe sections being formed similarly to the free ends of the pipe sections 6, 7, and 8 previously described. A similar pair of partitions 22 are arranged on the partition 4 at right angles thereto, forming a plurality of similar chambers, said chambers being closed by a curved perforated cap 47 secured to the head against the partitions 22 and in independently removable sections 47^a, 47^b, and 47^c respectively covering the chambers 19, 20, and 21. The partitions 22 are provided with channels 51 for the reception of packing strips 52, and a similar packing strip (not shown) is utilized upon an annular flange 50 around the sprinkler head to which the cap sections are secured by screws, as shown.

The valve members 45, referred to in the foregoing, are vertically movable gate valve members. The same general type of valve is shown in modified form in Fig. 11 according to which I provide a tapering casing designated 54, interposed in one of the pipe sections 42, 43, or 44, as the case may be. The valve element is also tapering and designated 55, the same having an opening 56 therein approximately midway the length thereof, said valve member being connected with an operating rod or stem 57, said stem extending through a suitable opening in the upper end of the casing 54. The stems 57, best shown in the modified form in Fig. 9, are connected with link members 58, said link members being in turn connected with rocker arms 59 pivoted on a bracket 60 extending from the tank 61 of a sprinkling cart or the like. Connecting rods 62 associate the inner ends of the rocker arms 59 with operating levers 63 pivoted in brackets 64 on the top of the tank 61. The levers 63 extend forwardly along the tank 61 to a point adjacent the driver's seat, not shown.

The outlet pipe for the tank 61 is designated 61^a, and is controllable by a valve 65, said valve being operable by a stem 66 connected with a lever 67, said lever extending forwardly to the driver's seat similarly to the levers 63. The housing 35 is mounted on the free end of the pipe section 61^a, by means of a threaded or other connection between the said pipe section and the throat 2.

I provide a further modification of my invention, the same being adapted for use in connection with the housing 1 of the preferred form of my invention shown in Fig. 1. In this instance I provide a plug system of valves for controlling the supply of liquid to the sprinklers, the same being best shown in Figs. 10 and 12.

Referring to Fig. 10, I have designated

the body of the sprinkler 70, the same having a throat portion 71 extending therefrom. The free end of the throat portion 71 is formed with an annular flange 72 and is 5 hingedly connected as at 73 with a supply pipe 74 formed with a complementary annular flange 75 engageable with the annular flange 72, a gasket 76 being interposed between said flanges for packing purposes. A 10 bracket 77 is mounted on the throat portion 71, said bracket having pivotally associated therewith a threaded rod 78 engageable with a bracket 79 mounted on the supply pipe 74, a wing nut 80 engaging said 15 threaded rod for clampingly engaging said flanges. The partition 5 has openings into which extend the inner ends of supply pipe sections carried in the body 70, said pipes being designated 81. A plurality of plugs 20 82 are adapted to be inserted into certain of the pipes 81, a rack 83 being arranged on the body 70 for receiving said plugs when not in use. A turning plug 86 is mounted in the supply pipe 74, said pipe being reduced as at 87 to accommodate said plug, the reduced portion 87 being provided with apertures 88. Thus the supply through the pipe 74 may be shut off when changing the 25 plugs.

30 From the foregoing description of my improved sprinkling device it will be readily apparent that by the provision of the same I am enabled to apply the device to various uses, either in the capacity of a hand sprinkling device or for use in connection with sprinkling carts. The simplicity of the device as well as the many detachable features of the same permit of a wide range of utility. If desired the perforate cap sections 35 40 in either instance may be removed and an extension or supplemental sprinkler may be added to the free end of either of the pipe sections carried in the bodies of the preferred and modified forms of my invention, 45 thereby permitting an extension of the sprinkling system. The angle of the supplemental sprinkler heads 27 and 28 may be changed by merely rotating the same on their pipes 25 and 26, or swinging the latter 50 at their joints with the pipe sections 31. Of course it is to be understood that I do not limit myself to the details of construction set forth since various modifications may be 55 made when utilizing the device in actual practice. It will be apparent that the perforate caps or cap sections may be removed in each instance and finer or coarser ones substituted and it is also apparent that any suitable strainer may be utilized as for instance at 3^a in Fig. 4.

60 From the above description taken in connection with the accompanying drawings, it

is thought that a clear and comprehensive understanding of the construction, operation, and advantages of my invention may 65 be had, and while I have shown and described my invention as embodying a specific structure, I desire that it be understood that such changes may be made in such structure as do not depart from the spirit 70 and scope of the invention as claimed.

I claim:

1. A sprinkler device comprising a housing having an inlet adapted for connection with a water supply, partitions in said housing dividing the interior thereof into separate compartments, pipes extending through two of said partitions and in open communication with the inlet of said housing, independently operable means for controlling the flow through said pipes respectively, the outer ends of said pipes opening into separate compartments, and each of said ends being adapted to be coupled to an extension pipe, and removable perforated plates covering the forward ends of the last named compartments respectively. 75

2. A sprinkler device comprising a housing having an inlet end adapted for connection with a water supply, partitions in said 90 housing dividing the interior thereof into separate compartments, pipes extending through two of said partitions and in open communication with the inlet end of said housing, independently operable means for 95 controlling the flow through said pipes respectively, the outer ends of said pipes opening into separate compartments, removable perforated plates covering the forward ends of the last named compartments respectively, 100 additional pipes carried by said housing and communicating with the inlet end thereof, extension pipes rotatably mounted on the outer ends of said additional pipes respectively, and sprinkler heads adjustably 105 mounted on the outer ends of the said extension pipes.

3. A sprinkler device comprising a housing having an inlet, partitions in said housing dividing the interior thereof into separate compartments, pipes extending through two of said partitions and in open communication with the inlet of said housing, independently operable means for controlling the flow through said pipes respectively, the 110 outer ends of said pipes opening into separate compartments, and each of said ends being adapted to be coupled to an extension pipe, removable perforated plates covering the forward ends of the last named compartments respectively, 115 a supply pipe, and a hinged connection between said housing and the inlet of said supply pipe. 120

EMILE PASSMANN.
